UNITED STATES PATENT OFFICE

GEORGE E. FRIEDRICH, OF SAN ANTONIO, TEXAS, ASSIGNOR TO EDWARD FRIEDRICH, OF SAN ANTONIO, TEXAS

REFRIGERATOR

Application filed April 8, 1932. Serial No. 604,092.

My invention relates to a certain new and improved refrigerator of the display type in which cooling coils are provided for establishing the low temperature desired.

5 An object of the invention is to provide an improved refrigerator in which the cooling coils are disposed in the bottom of the cabinet. Heretofore cabinets having the cooling coils in the bottom have been open to the objection 10 that filth accumulates around the coils,—i. e. pieces of meat and other food materials fall through the slatted shelves onto the cooling medium and accumulate there. It is, therefore, an object to provide a bottom-cooled 15 refrigerator of such construction and design as to avoid the accumulation of filth and hence to increase the sanitary factor of the cabinet.

Further objects are to provide a refrigerator which will maintain low even temperature 20 throughout the entire food chamber; to provide means to circulate the air over and through the coils and through the food chamber upwardly so as to prevent frost deposits on the coils and make it unnecessary to defrost the refrigerator at more or less frequent 25 intervals; to deliver conditioned cold air of proper humidity content to the entire refrigerator; to increase the available food storage and display space over those refrigerators 30 of like size which employ top or end cooling chambers; to provide a refrigerator in which the inside equipment is such that every piece can be removed without loosening screws or bolts so as to facilitate cleaning when necessary.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawings, in which:—

Figure 1 is a vertical longitudinal section of one end of a refrigerator embodying my invention, the section being taken substantially on the line 1—1 of Figure 3.

Figure 2 is a vertical longitudinal section of the other end of the refrigerator.

Figure 3 is a cross section on the line 3—3 of Figure 1.

Figure 4 is a cross section on the line 4—4 55 of Figure 2.

Figure 5 is a diagrammatic vertical longitudinal section of the refrigerator in full length.

Figure 6 is a detail perspective view of one 60 of the porcelain pans used to prevent fouling of the cooling coils.

In the drawings in which like numerals of reference designate like parts in all of the figures, 1 is the bottom of the cabinet which 65 includes a wooden base frame 2, suitable cork insulation 3 in the base, and a galvanized iron bottom plate 4 to retain the cork in position. Over the cork and framing is laid a wooden floor 5 covered with a sheath 6 of 70 copper.

The front wall of the refrigerator is composed of wood 7 and a set of glasses 67, the latter being inclined upwardly and inwardly and being spaced apart at the bottom by 75 suitable separators 13 laid on the sill 12 of the lower part of the front wall. The lower part of the front wall is provided with an inner wooden lining 8 and 10, stepped at 9, so as to provide along the center of the bottom of the cabinet a trough or recess between the walls 10 and provide a dead air space 11 between the cork 3 and the walls 9 and 10.

14 is a deflector on the inner side of the cabinet adjacent the bottom of the window 85 formed by the glasses 67 to deflect the air currents there.

15 is the rear wall of the cabinet which also has an inner lining 16—18, stepped at 17, and providing a dead air space 11a similar to the space 11. The rear wall is provided with a suitable number of door openings framed as at 19 and closed by doors 20 of suitable insulated construction.

Arranged along each inner lining wall 18 95 in the bottom of the cabinet but spaced from the floor thereof and above the steps 9 and 17 are angle irons 21 which run substantially the full length of the cabinet and serve as supports for the flanges 27 of the porcelain pans 100

22 and also has supports for the lower food shelf 33, the latter being preferably constructed of rods and wire so as to be foraminous.

The porcelain pans 22 have upwardly extending sides 23 that are apertured at 24 and have outwardly extending flanges 27 to rest on the supports 21 as before stated. The porcelain pans 22 are made in a series of sections or sub-pans. These sections or sub-pans 5 have underlying upstanding flanges 25 and overlying inverted V-shaped flanges 26 at the other end, the flange 25 of one pan section underlying the flange 26 of the other, the flanges, however, being spaced to provide 10 transverse air passages at intervals along the length of the pan series.

28 is the refrigerator coil pan which is provided with side walls 29 that lie in close proximity to the walls 10 and 18 respectively 20 and having outwardly extending flanges 30 at their tops to lie on the steps 9 and 17, thus dividing the space between the walls 10 and 18 into a lower air duct 32 and an upper space for coils between the bottom of the pan 28 25 and the pans 22. The bottom of the pan 28 is perforated at frequent intervals as at 31 so that the pan is a foraminous bottom pan to permit air to pass upwardly from the duct 32 through the perforations 31 into the coil 30 space.

34 is a fan housing located at one end of the cabinet and communicating through a funnel 35 with the air space 32 to deliver air from the fan 49 to the air space. The fan 35 housing 34 also communicates with a down-air duct 44 hereinafter again referred to.

The discharge funnel 35 has its spout 36 flattened and widened to conform to the cross section of the entrance of the air duct 32, 40 which duct can be seen by examination of Figure 1, and is of lesser depth at its far end than it is at its near or entrant end, the width being the same throughout. This is to compensate for the air passing through the apertures of the pan 28 in order to get a substantially uniform air discharge through the entire series of apertures 31 of the pan 28.

37 is a porcelain guard located over the fan housing and a portion of the funnel and 50 having a down flange 39 apertured at 40 and resting in the adjacent pan 22. The guard 37 at its other end lies on the angle iron support 38 which is secured to the porcelain lining wall 43. This porcelain lining wall 43 is spaced from the end wall of the cabinet to form the down-air duct 44. The end wall 41 of the cabinet is insulated with cork 3 and lined at 42 with a suitable lining of 55 copper plate or other suitable material.

60 Adjacent the housing 34 the end wall of the cabinet is provided with a service door opening 45 normally closed by a suitably insulated door 46 so that access to the motor and fan can be had when necessary.

65 The motor 48 of the fan is carried by a

suitable bracket 47 secured to the cross angle 38 of the lining 43 and suitable oil ducts 50 are provided from the motor bearings, which ducts lead up to the pan 28 into the food space of the cabinet so that oiling of the 70 motor bearings may be effected from the inside of the food cabinet when found desirable.

51 is the current lead-in wires to the motors. They are embedded in a suitable lead covering 75 for protection.

The other end wall 52 of the cabinet is insulated by cork 3 and has a copper wall covering 53 similar to the first mentioned end wall. There is also a porcelain lining 54 80 for the food chamber spaced from the end wall sheathing 53 to form an air space 56. The lower end of the porcelain end wall lining 54 is provided with a gutter 55 over which the adjacent flange 26 of the adjacent 85 pan 22 projects, leaving a space for air passage as in the other pan joints.

57 is the top wall of the refrigerator and it, too, is insulated with cork 3 and lined with wood 58—59, the lining 58 constituting 90 upper framing for the reception of the glasses 67 and their upper spaces. The top wall is provided with a recess that has a copper lining constituting an inverted trough 95 of rectangular form in cross section, the bottom of which is closed by a porcelain plate 62, thereby constituting a top air duct 60. This air duct, like the lower one, is of greater depth at the left hand end of the cabinet than at the right hand end, that is to say 100 the cross sectional area of the upper air duct is greatest at its exit end and the cross sectional area of the lower air duct is greatest at its entrant end, the exit end of the upper duct and the entrant end of the lower duct being located at the same end of the refrigerator. The upper duct communicates with the top of the down-air duct 44 so that when the motor is running the fan draws the air from the upper duct down the duct 44 105 and delivers it into the lower duct from whence it filters out through the apertures 31, passes between the cooling coil convolutions and under the pan 22 where it is deflected toward the front and back of the refrigerator and passes to the apertures 24 beneath the shelf 33, filtering through the shelf and around the articles thereon, if there be any. The air passing upwardly 110 from the shelf 33 through the food chamber is gathered by the upper air duct and returned to the fan, it being understood that the upper air duct has its plate 62 perforated.

115 The lower wall of the upper air duct is formed of a series of porcelain plates 62 in the preferred embodiment of the invention, which rest on the hard rubber door slides 64 secured to the channel cross support 63, these door slides serving to support the vanish- 120 125

ing doors 65 in the rear wall of the refrigerator. These doors 65 rest on sills 66 when in the closed position but may be lifted upwardly beneath the top of the cabinet when 5 access of the interior is desired through the openings 70. The doors 65 and the means for mounting them may be, and preferably are, of the construction disclosed in my application for Patent, Serial No. 535,524.

10 Within the food chamber, adjacent midway the height thereof and below the openings 70, are longitudinal angle iron supports 68 for the upper food shelf 69, the latter also being of the open wire type. The support 68 which 15 is adjacent the window 67 is preferably set in from the window to leave an air space 71 so as to prevent fogging of the windows by enabling the cool air currents to be passed up along the inner glass.

20 In the practical construction of my invention in a refrigerator of about eleven and one-half feet in length, the coil pan 28 has approximately 288 $\frac{3}{8}$ " apertures 41 in its door length while each plate 62 is provided 25 with 10 $\frac{3}{4}$ " apertures, this being found to be a practical proportioning of the openings relative to each other.

While I have described a preferred embodiment of my invention and have disclosed the 30 same in the drawings I desire it understood that I do not wish to be limited to the specific details of construction shown and described or the specific materials mentioned as they may be varied from time to time as best 35 refrigerator practice may dictate so long as the structure and combinations of elements come within the terms of the appended claims.

What I claim is:

1. In a refrigerator, a cabinet having a 40 food compartment extending substantially the full length, depth, and height of the cabinet, said cabinet having a recessed bottom and a recessed top, air ducts extending from end to end of said cabinet and located 45 in the recesses of the top and bottom, a down-air duct located at one end of the cabinet and connecting the top and bottom ducts, a fan housing in the bottom of the cabinet with which said down-air duct and said bottom duct communicate, a fan in said fan housing, said top and bottom ducts having their opposing faces perforated, a food shelf supported in 50 said cabinet adjacent the recessed bottom and over the lower air duct, and cooling means located between said shelf and the lower air duct.

2. In a refrigerator, a cabinet having a 60 food compartment extending substantially the full length, depth and height of the cabinet, said cabinet having a recessed bottom and a recessed top, air ducts extending from end to end of said cabinet and located in the recesses of the top and bottom, a down-air duct located at one end of the cabinet and connecting 65 the top and bottom ducts, a fan housing in the

the bottom of the cabinet with which said down-air duct and said bottom duct communicate, said top and bottom air ducts progressively decreasing in height from the end adjacent said down-air duct to the opposite end 70 of the cabinet, a fan in said fan housing, said top and bottom ducts having their opposing faces perforated, a food shelf supported in said cabinet adjacent the recessed bottom and over the lower air duct, and cooling means 75 located between said shelf and the lower air duct.

3. In a refrigerator, a cabinet having a food compartment extending substantially the full length, depth and height of the cabinet, said cabinet having a recessed bottom and a recessed top, air ducts extending from end to end of said cabinet and located in the recesses of the top and bottom, a down-air duct located at one end of the cabinet and connecting 80 the top and bottom ducts, a fan housing in the bottom of the cabinet with which said down-air duct and said bottom duct communicate, a fan in said fan housing, said top and bottom ducts having their opposing faces perforated, a food shelf supported in said cabinet adjacent the recessed bottom and over the lower air duct, and cooling means located between said shelf and the lower air duct.

4. In a refrigerator, a cabinet having a food compartment extending substantially the full length, depth, and height of the cabinet, said cabinet having a recessed bottom and a recessed top, air ducts extending from end to end of said cabinet and located in the recesses of the top and bottom, a down-air duct located at one end of the cabinet and connecting the top and bottom ducts, a fan housing in the bottom of the cabinet with which said down-air duct and said bottom duct communicate, a fan in said fan housing, said top and bottom ducts having their opposing faces perforated, a food shelf supported in 100 said cabinet adjacent the recessed bottom and over the lower air duct, and cooling means located between said shelf and the lower air duct, said cooling means comprising coils located in the recesses of the bottom of the cabinet above the lower air duct and below the 105 shelf.

5. In a refrigerator, a cabinet having a food compartment extending substantially the full length, depth, and height of the cabinet, said cabinet having a recessed bottom and a recessed top, air ducts extending from end to end of said cabinet and located in the recesses of the top and bottom, a down-air duct located at one end of the cabinet and connecting the top and bottom ducts, a fan housing in the bottom of the cabinet with which said down-air duct and said bottom duct communicate, a fan in said fan housing, said top and bottom ducts having their opposing faces perforated, 120 a food shelf supported in said cabinet adj- 125

- cent the recessed bottom and over the lower air duct, cooling means located between said shelf and the lower air duct, and a pan located over said cooling means and below said shelf and having foraminous side flanges, all being arranged so that the air discharged upwardly through the holes in the lower air duct will pass over said coils and under said pan and through the side flange openings thereof into the space beneath the shelf and from thence through the shelf upwardly to the upper air duct and return to the fan via the down-air duct. 6. In a refrigerator, a cabinet having a food compartment extending substantially the full length, depth, and height of the cabinet, said cabinet having a recessed bottom and a recessed top, air ducts extending from end to end of said cabinet and located in the recesses of the top and bottom, a down-air duct located at one end of the cabinet and connecting the top and bottom ducts, a fan housing in the bottom of the cabinet with which said down-air duct and said bottom duct communicate, a fan in said fan housing, said top and bottom ducts having their opposing faces perforated, a food shelf supported in said cabinet adjacent the recessed bottom and over the lower air duct, cooling means located between said shelf and the lower air duct, and a pan located over said cooling means and below said shelf and having foraminous side flanges, all being arranged so that the air discharged upwardly through the holes in the lower air duct will pass over said coils and under said pan and through the side flange openings thereof into the space beneath the shelf and from thence through the shelf upwardly into the upper air duct and return to the fan via the down-air duct, said pan comprising a series of pan sections having overlapping portions spaced apart to provide guarded air passages at intervals across the pan from one end of the pan to the other. 7. In a refrigerator, a cabinet having a food compartment extending substantially the full length, depth, and height of the cabinet, said cabinet having a recessed bottom and a recessed top, air ducts extending from end to end of said cabinet and located in the recesses of the top and bottom, a down-air duct located at one end of the cabinet and connecting the top and bottom ducts, a fan housing in the bottom of the cabinet with which said down-air duct and said bottom duct communicate, a fan in said fan housing, said top and bottom ducts having their opposing faces perforated, a food shelf supported in said cabinet adjacent the recessed bottom and over the lower air duct, and cooling means located between said shelf and the lower air duct, a second food shelf located above the first food shelf, the first food shelf being of an area substantially that of the horizontal cross section of the food compartment of the cabinet, and the second shelf being of a depth less than that of the food compartment so as to leave an up-air passage along one edge of the shelf. 8. In a refrigerator, a cabinet having a food compartment extending substantially the full length, depth and height of the cabinet, said cabinet having a recessed bottom and a recessed top, air ducts extending from end to end of said cabinet and located in the recesses of the top and bottom, a down-air duct located at one end of the cabinet and connecting the top and bottom ducts, a fan housing in the bottom of the cabinet with which said down-air duct and said bottom duct communicate, said top and bottom air ducts progressively decreasing in height from the end adjacent said down-air duct to the opposite end of the cabinet, a fan in said fan housing, said top and bottom ducts having their opposing faces perforated, a food shelf supported in said cabinet adjacent the recessed bottom and over the lower air duct, and cooling means located between said shelf and the lower air duct, a second food shelf located above the first food shelf, the first food shelf being of an area substantially that of the horizontal cross section of the food compartment of the cabinet, and the second shelf being of a depth less than that of the food compartment so as to leave an up-air passage along one edge of the shelf. 9. In a refrigerator, a cabinet having a food compartment extending substantially the full length, depth and height of the cabinet, said cabinet having a recessed bottom and a recessed top, air ducts extending from end to end of said cabinet and located in the recesses of the top and bottom, a down-air duct located at one end of the cabinet and connecting the top and bottom ducts, a fan housing in the bottom of the cabinet with which said down-air duct and said bottom duct communicate, a fan in said fan housing, said top and bottom ducts having their opposing faces perforated, a foraminous food shelf supported in said cabinet adjacent the recessed bottom and over the lower air duct, and cooling means located between said shelf and the lower air duct, a second food shelf located above the first food shelf, the first food shelf being of an area substantially that of the horizontal cross section of the food compartment of the cabinet, and the second shelf being of a depth less than that of the food compartment so as to leave an up-air passage along one edge of the shelf. 10. In a refrigerator, a cabinet having a food compartment extending substantially the full length, depth and height of the cabinet, said cabinet having a recessed bottom and a recessed top, air ducts extending from end to end of said cabinet and located in the recesses of the top and bottom, a down-air duct located at one end of the cabinet and connecting the top and bottom ducts, a fan

- housing in the bottom of the cabinet with which said down-air duct and said bottom duct communicate, a fan in said fan housing, said top and bottom ducts having their opposing faces perforated, a food shelf supported in said cabinet adjacent the recessed bottom and over the lower air duct, cooling means located between said shelf and the lower air duct, said cooling means comprising coils located in the recesses of the bottom of the cabinet above the lower air duct and below the shelf, a second food shelf located above the first food shelf, the first food shelf being of an area substantially that of the horizontal cross section of the food compartment of the cabinet, and the second shelf being of a depth less than that of the food compartment so as to leave an up-air passage along one edge of the shelf.
11. In a refrigerator, a cabinet having a food compartment extending substantially the full length, depth, and height of the cabinet, said cabinet having a recessed bottom and a recessed top, air ducts extending from end to end of said cabinet and located in the recesses of the top and bottom, a down-air duct located at one end of the cabinet and connecting the top and bottom ducts, a fan housing in the bottom of the cabinet with which said down-air duct and said bottom duct communicate, a fan in said fan housing, said top and bottom ducts having their opposing faces perforated, a food shelf supported in said cabinet adjacent the recessed bottom and over the lower air duct, cooling means located between said shelf and the lower air duct, said cooling means comprising coils located in the recesses of the bottom of the cabinet above the lower air duct and below the shelf, a second food shelf located above the first food shelf, the first food shelf being of an area substantially that of the horizontal cross section of the food compartment of the cabinet, and the second shelf being of a depth less than that of the food compartment so as to leave an up-air passage along one edge of the shelf.
13. In a refrigerator, a cabinet having a bottom, a top, ends, a front and a back with suitable doors for gaining access to the interior thereof, a trough in the bottom of said cabinet extending from end to end and of less depth than that of the chamber of the cabinet, a pan of U-shape in cross section set into said trough and dividing it into a lower air duct and an upper cooling medium receiving chamber, said U-shaped pan having a perforated bottom, a cooling means located within the pan, a food shelf located above the cooling means and of a depth approximately equal to that of the food chamber of the cabinet, and means extending along the front and back of said cabinet within said chamber for supporting said shelf, a fan to force air into said air duct, and withdraw air from the chamber of the cabinet above the shelf.
14. In a refrigerator, a cabinet having a bottom, a top, ends, a front and a back with suitable doors for gaining access to the interior thereof, a trough in the bottom of said cabinet extending from end to end and of less depth than that of the chamber of the cabinet, a pan of U-shape in cross section set into said trough and dividing it into a lower air duct and an upper cooling medium receiving chamber, said U-shaped pan having a perforated bottom and gradually decreasing in cross sectional area from one end to the other, a cooling means located within the pan, a food shelf located above the cooling means and of a depth approximately equal to that of the food chamber of the cabinet, and means extending along the front

and back of said cabinet within said chamber for supporting said shelf, a fan to force air into said air duct and withdraw air from the chamber of the cabinet above the shelf.

15. In a refrigerator, a cabinet having a bottom, a top, ends, a front and a back with suitable doors for gaining access to the interior thereof, a trough in the bottom of said cabinet extending from end to end and of less depth than that of the chamber of the cabinet, a pan of U-shape in cross section set into said trough and dividing it into a lower air duct and an upper cooling medium receiving chamber, said U-shaped pan having a perforated bottom and gradually decreasing in cross sectional area from one end to the other, a cooling means located within the pan, a food shelf located above the cooling means and of a depth approximately equal to that of the food chamber of the cabinet, means extending along the front and back of said cabinet within said chamber for supporting said shelf, a fan to force air into said air duct, and a return air duct located at the top of the cabinet and one end wall thereof to return the warmer air to the fan.

16. In a refrigerator, a cabinet having a bottom, a top, ends, a front and a back with suitable doors for gaining access to the interior thereof, a trough in the bottom of said cabinet extending from end to end and of less depth than that of the chamber of the cabinet, a pan of U-shape in cross section set into said trough and dividing it into a lower air duct and an upper cooling medium receiving chamber, said U-shaped pan having a perforated bottom, a cooling means located within the pan, a food shelf located above the cooling means and of a depth approximately equal to that of the food chamber of the cabinet, means extending along the front and back of said cabinet within said chamber for supporting said shelf, a fan to force air into said air duct and withdraw air from the chamber of the cabinet above the shelf, and a pan having sides and outwardly extending flanges to rest on said shelf supporting means and located above the cooling means, said last named pan having its sides perforated and having transversely disposed air-passing slots at intervals along its length.

17. In a refrigerator, a cabinet having a bottom, a top, ends, a front and a back with suitable doors for gaining access to the interior thereof, a trough in the bottom of said cabinet extending from end to end and of less depth than that of the chamber of the cabinet, a pan of U-shape in cross section set into said trough and dividing it into a lower air duct and an upper cooling medium receiving chamber, said U-shaped pan having a perforated bottom and gradually decreasing in cross sectional area from one end to the other, a cooling means located within the pan, a food shelf located above the cooling means

and of a depth approximately equal to that of the food chamber of the cabinet, means extending along the front and back of said cabinet within said chamber for supporting said shelf, a fan to force air into said air duct and withdraw air from the chamber of the cabinet above the shelf, and a pan having sides and outwardly extending flanges to rest on said shelf supporting means and located above the cooling means, said last named pan having its sides perforated and having transversely disposed air-passing slots at intervals along its length.

18. In a refrigerator, a cabinet having a bottom, a top, ends, a front and a back with suitable doors for gaining access to the interior thereof, a trough in the bottom of said cabinet extending from end to end and of less depth than that of the chamber of the cabinet, a pan of U-shape in cross section set into said trough and dividing it into a lower air duct and an upper cooling medium receiving chamber, said U-shaped pan having a perforated bottom and gradually decreasing in cross sectional area from one end to the other, a cooling means located within the pan, a food shelf located above the cooling means and of a depth approximately equal to that of the food chamber of the cabinet, means extending along the front and back of said cabinet within said chamber for supporting said shelf, a fan to force air into said air duct, a return air duct located at the top of the cabinet and one end wall thereof to return the warmer air to the fan, and a pan having sides and outwardly extending flanges to rest on said shelf supporting means and located above the cooling means, said last named pan having its sides perforated and having transversely disposed air-passing slots at intervals along its length.

19. In a refrigerator, a cabinet having a bottom, a top, ends, a front and a back with suitable doors for gaining access to the interior thereof, a trough in the bottom of said cabinet extending from end to end and of less depth than that of the chamber of the cabinet, a pan of U-shape in cross section set into said trough and dividing it into a lower air duct and an upper cooling medium receiving chamber, said U-shaped pan having a perforated bottom, a cooling means located within the pan, a food shelf located above the cooling means and of a depth approximately equal to that of the food chamber of the cabinet, means extending along the front and back of said cabinet within said chamber for supporting said shelf, a fan to force air into said air duct and withdraw air from the chamber of the cabinet above the shelf, a series of food-catching pans located below said shelf and above said cooling instrumentalities and having spaced overlapping ends, vertical foraminous sides and flanges for engaging said shelf supporting means whereby

to pass air from below said pans through the sides and between the overlapped ends thereof to the space above said pans.

20. In a refrigerator, a cabinet having a bottom, a top, ends, a front and a back with suitable doors for gaining access to the interior thereof, a trough in the bottom of said cabinet extending from end to end and of less depth than that of the chamber of the cabinet, a pan of U-shape in cross section set into said trough and dividing it into a lower air duct and an upper cooling medium receiving chamber, said U-shaped pan having a perforated bottom and gradually decreasing in cross sectional area from one end to the other, a cooling means located within the pan, a food shelf located above the cooling means and of a depth approximately equal to that of the food chamber of the cabinet, and means extending along the front and back of said cabinet within said chamber for supporting said shelf, a fan to force air into said air duct and withdraw air from the chamber of the cabinet above the shelf, a series of food-catching pans located below said shelf and above said cooling instrumentalities and having spaced overlapping ends, vertical foraminous sides and flanges for engaging said shelf supporting means whereby to pass air from below said pans through the sides and between the overlapped ends thereof to the space above said pans.

21. In a refrigerator, a cabinet having a bottom, a top, ends, a front and a back with suitable doors for gaining access to the interior thereof, a trough in the bottom of said cabinet extending from end to end and of less depth than that of the chamber of the cabinet, a pan of U-shape in cross section set into said trough and dividing it into a lower air duct and an upper cooling medium receiving chamber, said U-shaped pan having a perforated bottom and gradually decreasing in cross sectional area from one end to the other, a cooling means located within the pan, a food shelf located above the cooling means and of a depth approximately equal to that of the food chamber of the cabinet, means extending along the front and back of said cabinet within said chamber for supporting said shelf, a fan to force air into said air duct, and a return air duct located at the top of the cabinet and one end wall thereof to return the warmer air to the fan, a series of food-catching pans located below said shelf and above said cooling instrumentalities and having spaced overlapping ends, vertical foraminous sides and flanges for engaging said shelf supporting means whereby to pass air from below said pans through the sides and between the overlapped ends thereof to the space above said pans.

22. In a refrigerator, a cabinet having a

bottom, a top, ends, a front and a back with suitable doors for gaining access to the interior thereof, a trough in the bottom of said cabinet extending from end to end and of less depth than that of the chamber of the cabinet, a pan of U-shape in cross section set into said trough and dividing it into a lower air duct and an upper cooling medium receiving chamber, said U-shaped pan having a perforated bottom, a cooling means located within the pan, a food shelf located above the cooling means and of a depth approximately equal to that of the food chamber of the cabinet, means extending along the front and back of said cabinet within said chamber for supporting said shelf, a fan to force air into said air duct and withdraw air from the chamber of the cabinet above the shelf, a series of food-catching pans located below said shelf and above said cooling instrumentalities and having spaced overlapping ends, vertical foraminous sides and flanges for engaging said shelf supporting means whereby to pass air from below said pans through the sides and between the overlapped ends thereof to the space above said pans, said overlapped ends comprising an upstanding flange and an inverted V-shaped flange held over the upstanding flange in spaced relation thereto.

23. In a refrigerator, a cabinet having a transparent front, rear doors to the food chamber, and a foraminous shelf located across the depth and length of the food chamber below the transparent front; a longitudinally extending trough in the bottom of said cabinet containing a space, an air duct within said trough and having provisions to discharge air at numerous places upwardly into the space above it, a cooling coil in said space above said air duct, a return air duct along the top of the cabinet and down one end thereof to communicate with the first-mentioned air duct, a fan in communication with said ducts for circulating air therethrough and upwardly through the food chamber, and means to prevent filth dropping onto said coil from said shelf.

24. In a refrigerator, cabinet having a transparent front, rear doors to the food chamber, and a foraminous shelf located across the depth and length of the food chamber below the transparent front; a longitudinally extending trough in the bottom of said cabinet containing a space, an air duct within said trough and having provisions to discharge air at numerous places upwardly into the space above it, a cooling coil in said space above said air duct, a return air duct along the top of the cabinet and down one end thereof to communicate with the first-mentioned air duct, a fan in communication with said ducts for circulating air therethrough and upwardly through the food chamber, and means to prevent filth dropping

onto said coil from said shelf, said means comprising a pan above the coil and beneath the shelf and having vertical walls perforated to pass the air from the space beneath to 5 the space above said pan.

25. In a refrigerator, a cabinet having a food compartment extending substantially the full length, depth, and height of the cabinet, said cabinet having a recessed bottom 10 and a top, air ducts extending from end to end of said cabinet and located in the top and bottom, a down-air duct located at one end of the cabinet and connecting the top and bottom ducts, a fan housing in the bottom 15 of the cabinet with which said down-air duct and said bottom duct communicate, a fan in said fan housing, said top and bottom ducts having their opposing faces perforated, a food shelf supported in said cabinet adjacent 20 the recessed bottom and over the lower air duct, and cooling means located between said shelf and the lower air duct.

26. In a refrigerator, a cabinet having a food compartment extending substantially 25 the full length, depth and height of the cabinet, said cabinet having a recessed bottom and a top, air ducts extending from end to end of said cabinet and located in the top and bottom, a down-air duct located at one 30 end of the cabinet and connecting the top and bottom ducts, a fan housing in the bottom of the cabinet with which said down-air duct and said bottom duct communicate, said top and bottom air ducts progressively decreasing 35 in height from the end adjacent said down-air duct to the opposite end of the cabinet, a fan in said fan housing, said top and bottom ducts having their opposing faces perforated, a food shelf supported in said 40 cabinet adjacent the recessed bottom and over the lower air duct, and cooling means located between said shelf and the lower air duct.

27. In a refrigerator, a cabinet having a food compartment extending substantially 45 the full length, depth, and height of the cabinet, said cabinet having a recessed bottom and a top, air ducts extending from end to end of said cabinet and located in the top and bottom, a down-air duct located at one end of 50 the cabinet and connecting the top and bottom ducts, a fan housing in the bottom of the cabinet with which said down-air duct and said bottom duct communicate, a fan in said fan housing, said top and bottom ducts having 55 their opposing faces perforated, a food shelf supported in said cabinet adjacent the bottom and over the lower air duct, cooling means located between said shelf and the lower air duct, and a pan located over said 60 cooling means and below said shelf and having foraminous side flanges, all being arranged so that the air discharged upwardly through the holes in the lower air duct will pass over said coils and under said pan and 65 through the side flange openings thereof into

the space beneath the shelf and from thence through the shelf upwardly into the upper air duct and return to the fan via the down-air duct, said pan comprising a series of pan sections having overlapping portions spaced apart to provide guarded air passages at intervals across the pan from one end of the pan to the other. 70

28. In a refrigerator, a cabinet having a transparent front, rear doors to the food chamber, and a foraminous shelf located across the depth and length of the food chamber below the transparent front; a longitudinally extending trough in the bottom of said cabinet containing a space, an air duct within 75 said trough and having provisions to discharge air at numerous places upwardly into the space above it, a cooling coil in said space above said air duct, a return air duct along the top of the cabinet and down one end 80 thereof to communicate with the first-mentioned air duct, a fan in communication with said ducts for circulating air therethrough and upwardly through the food chamber, and means to prevent filth dropping onto said 85 coil from said shelf, said means comprising a pan above the coil and beneath the shelf and having vertical walls perforated to pass the air from the space beneath to the space above said pan, said pan having spaced overlapped ends, said overlapped ends comprising an upstanding flange and an inverted V-shaped flange held over the upstanding flange in spaced relation thereto. 90
